John Reed

Patent

9461 X

The schedule referred to in these Letters Patent and making part of the same containing a description in shorthand of the said John Reed himself of his improvement in the said Mill (carriage track and dog) — — —

To all persons to whom these presents shall come. Be it known that John Reed of Marshfield in the County of Plymouth and Commonwealth of Massachusetts, a machinist, have invented and put into operation a new and useful improvement in the mode or manner of confining, moving and adjusting the log to be sawed, and which is described in the following words. The principle part of my improvement consists in slides a slide board, lever, hinge brace and two right angle dogs, which are made of rough timber and all constructed and applied in the following manner. The slide plate A. is four four to five feet in length seven or eight inches in width and about half an inch in thickness except two inches of the front edge on which the log slides, which is one inch.

The back edge is turned up two or three inches with a lip to receive the slides and to support one edge of it. The other slides B. B. are about two feet in length three or four inches in width, turned up in the same manner as the former to receive and support the other edge of the slides. The slide C. is about three feet in length, three inches in width, an inch in thickness, grooved in each edge for the slides. The under side of this slide is notched from end to end, allowing four notches to the inch and a quarter, thereby, giving the slide bends. The distances of these notches from each other may be increased or diminished as occasion may require. The

lever D, to which the hand is attached, whereby the slide is moved is about three feet in length, of which and which is sufficient for strength. The end of this lever is an arm of about one foot in length two inches in diameter, and is at right angles with the vertical plane. The other end of this arm is a crank of about three or four inches in length. The hand E, is about eight or ten inches in length three in width and three in thickness. In the middle of this hand is a hole, one inch and a half in diameter which is to receive one end of the screw by which the hand is suspended. This hand is made of cast iron with steel and fitted to the middle of the slide. Under this hand is a straight bar, to which a weight is suspended. The arms F, are eight weight, the horizontal part of which are six feet and six inches in length three inches in thickness. The perpendicular parts are each nine inches in height five and a half inches square. In each of these are three or four holes in which rough iron or steel teeth are forced for confining the log. These arms are fixed upon the slide by a screw joint at the outer end. Two pieces of common iron are fastened, one at each end of the slide, sloping back at an angle of forty-five degrees. The arm G, is used for getting the log, it is constructed with a lock joint, by which the motion required is obtained, in this manner may be balanced by a small brace about five feet in length which is placed at an angle of about forty-five degrees in a mortise in a post which lays parallel with carriage. In the upper end of said brace is a mortise to receive one end of a counterbrace about one foot in length, which is confined by a bolt. In the backward motion of the carriage the lever (D) comes in contact with said brace, by which it is caused to turn the log is set by

By the joint of the circular arm in the brace, the carriage is permitted to pass forward, without giving motion to the lever. The application of the machine is as follows. Place the plate A. on the carriage stocks, cover with the inner edge, bolt it fast, place the two other slides B.C. back of it so far as to admit the slider D. to slide between them both down also. Place the axis of the lever D. between the two short slides. Let the ^{hand} come directly under the slider. Let the axis of the lever be firmly hung in wood or iron, and let the long arm of the lever D. extend a little without the carriage parallel with the plate. Place the knee E. about the distance of the length of its horizontal part back of the end of the lever of height sufficient to give the proper motion to the lever. A similar apparatus may be used at the head stocks. In using this machine, the log is rolled on to its proper place. The dogs are driven in, and the combats dropped in the back of the dogs upon the sloped pieces, by which the log is firmly held. To change the motion of the slider, it is only necessary to depress one end of the hand, and the weight, sliding on the bail will throw the other end into the notches. With this apparatus the log is held to be squared into lumber of any proportion, without chisel, saw or any improvement is the motion of the slider, the hand, weight and lever, the back joint of the knee the swivel brace the right angle dogs and the method of confining them as above described, and their arrangement. In testifying that the above is a true specification of my said improvement as my invention, I have caused to set my hand this twentieth day of January 1836. - *John C. Reed*
